UNITED STATES PATENT OFFICE.

EDWARD B. JACOBSON, OF PITTSFIELD, MASSACHUSETTS, ASSIGNOR TO HENDEE MANUFACTURING COMPANY, OF SPRINGFIELD, MASSACHUSETTS, A CORPORATION OF MASSACHUSETTS.

INDUCTION-COIL.

1,268,468.

Specification of Letters Patent. Patented June 4, 1918.

Application filed December 3, 1913. Serial No. 804,532.

To all whom it may concern:

Be it known that I, EDWARD B. JACOBSON, a citizen of the United States, residing at Pittsfield, in the county of Berkshire, State of Massachusetts, have invented certain new and useful Improvements in Induction-Coils, of which the following is a description, reference being had to the accompanying drawing and to the figures of reference 10 marked thereon.

The invention relates to new and useful improvements in induction coils, and more particularly to coils of this character used as sparking coils for an ignition system for 15 combustion engines.

An object of the invention is to provide means in connection with the coils for directing and shortening the path of the magnetic flux so as to increase the efficiency of 20 the current induced in the secondary coil.

In the drawings, which show by way of illustration one embodiment of the invention,

Figure 1 is a side elevation of an induction coil embodying my improvements;

Fig. 2 is a longitudinal sectional view through the same;

Fig. 3 is a sectional view on the line 3, 3 of Fig. 2.

The induction coil consists generally of a core of soft iron on which is placed a primary coil. On the outside of this primary coil is located a secondary coil. At each end of the core is a magnetic plate, which is 30 extended beyond the core so as to overlap the primary coil and partially overlap the secondary coil.

Referring more in detail to the drawings, my improved induction coil as herein shown 40 consists of a core 1, which is made up of a bundle of soft iron wires arranged side by side and extending longitudinally of the core.

Located on said core is a primary coil 2, 45 which is made up of suitable layers of insulating material, such as paper or the like, and a series of windings of relatively coarse wire. Outside of the primary coil is a secondary coil 3, which is preferably formed of a fine enamel covered wire, and this secondary coil is preferably surrounded by a rubber cover 4, which entirely incloses the coil and protects the same from moisture.

After the coils have been formed or assembled, as above noted, a disk of insulating

material 5 is placed at each end of the core, and this disk is formed with an opening 6 of substantially the same diameter as the core, and a recess 7, which extends beyond the primary coil and partially overlaps the 60 secondary coil. There is a disk 5 at each end of the coils. A magnetic plate 8 is located in the recess in one of the disks and this plate carries a rod 9, which is firmly secured thereto in any desired way. The rod 65 9 extends centrally through the core. A magnetic plate 10 fitting the recess 7 in the other disk is provided with an opening which extends over the rod 9. This opening is threaded and the threads in the opening 70 coöperate with threads on the rod so that the magnetic plates also serve to hold the disks 5 in place. The magnetic plate 8 may be provided with suitable openings through which the wires from the coils extend.

It is to be noted that these magnetic plates 8 and 10 extend beyond the primary coil and overlap the secondary coil substantially throughout its diameter. This magnetic plate directs the flow of the magnetic 80 flux so as to assure said flux passing wholly outside of the primary coil. In other words, it directs the return path of the magnetic flux so that there is substantially no return through the primary coil, which, of course, 85 would be wasted.

Then again, these magnetic plates serve to shorten the air gap through which the magnetic flux flows, and thereby increase the effective current induced in the secondary coil.

The magnetic plates 8 and 10 are formed with recesses in the inner faces thereof, to receive the core 1, whereby a more efficient circuit is established for the flow of flux.

It is obvious that minor changes in the 95 details of construction may be made without departing from the spirit of the invention, as set forth in the appended claims.

Having thus described my invention, what I claim is:

1. An induction coil comprising a core, a primary coil and a secondary coil extending about said core, an insulating disk at each end of the core, each disk having a recess formed therein, a magnetic plate located in each recess and extending so as to cover the primary coil and overlap the secondary coil, each of said magnetic plates having a recessed engagement with said coil, and means for connecting said magnetic plates. 110

2. An induction coil comprising a core, a primary coil and a secondary coil extending about said core, an insulating disk at each end of the core, each disk having a recess formed therein, a magnetic plate located in each recess and extending so as to cover the primary coil and overlap the secondary coil, each of said magnetic plates having a recessed engagement with said coil, and a

rod extending centrally through said core 10 and threaded into said magnetic plates.

In testimony whereof, I affix my signature, in the presence of two witnesses.

EDWARD B. JACOBSON.
